UNITED STATES PATENT OFFICE.

AUGUST MARIOLLE, OF OAKLAND, CALIFORNIA, AND GASTON MARIOLLE AND RAYMOND MARIOLLE, OF NEW YORK, N. Y.

CURTAIN-SIGN EXHIBITOR.

Application filed October 24, 1923. Serial No. 670,533.

Our invention relates to curtain sign exhibitors of the type wherein a plurality of sign rolls are contained within the apparatus and automatically unrolled one after the other for display at a viewing panel.

The improvements have particular reference to the type of mechanism and illuminating and sign system disclosed in Patent No. 851,297 of April 23, 1907 issued to August Mariolle, one of the joint inventors hereto, and the principal objects of the improvements are the general perfection of the apparatus and system in providing amongst many features: a simpler mechanism easily applied to any size exhibitor by the mere extension of certain chains and simple longitudinal members; a driving element continuously running in one direction, eliminating thereby all stop or reverse gears, cams, et cetera; a mechanism simultaneously exhibiting oppositely disposed display curtains, one at each side of the box with a common illuminating system between them; the use of a transparent mirror over the viewing panel to further increase the illusionary effect of the displayed curtains; the provision of a single traveling trip for actuating all the movements of the curtains, reels and the electric lamp switches as well, and other features cooperating to render the apparatus more efficient, which will appear as the description proceeds.

In the drawings appended hereto, Figure 1 is a view of our improved apparatus as seen by a person in front of one of the two viewing panels, the other panel being directly in back and in line therewith.

Figure 2 is a vertical cross-section of the exhibitor on the line 2—2 of Figure 1.

Figure 3 is a similar section taken along the line 3—3 of Figure 1 to show the electrical switches and trips.

Figure 4 is an enlarged view of one of the heads of the roll-carrying reel.

Figure 5 shows a curtain roll and method of securing a curtain thereto.

Figure 6 is a separate view of one of the curtain rods.

Figures 7 and 8 are, respectively, rear and edge views of one of the traveling slats.

Figure 9 is a fragmentary view showing one of the double V hooks on the traveling slats for hooking the curtain rods.

Figure 10 is an end view of a roller showing a curtain partly wound thereon.

Figures 11 and 12 are details of the slat pawl trip.

Figures 13 and 14 are details of the electric switches and trips.

Figure 15 is a detail perspective of one of the end arms 32.

Figure 16 is a detail cross section of the slat 8 and showing the pawls 10 also in cross section.

In Figures 1 and 2 a box or frame is indicated at 1 and has the usual front molding 1' omitted in Figure 1 to show the interior, the said molding normally covering the working elements of the machine from view and reducing a central viewing panel to about the size of the unrolled curtain 2. Usually, between the observer and the curtain, and removably positioned within the opening of the molding constituting the viewing panel, is a transparent mirror; that is, a glass mirror silvered so thinly that it may easily be looked through when the superior illumination is directed through it to the observer, but reflects the observer when the superior illumination is upon him.

In Figure 2 the mirror is indicated at 3. The curtain rolls 4 have spaced notches 4' for the reception of hooks 3' at the inner end of curtain 2. The rolls 4 are carried in revolving reels 5 at each end of the frame, and in the complete apparatus four reels are used as shown in Figure 2.

At the eight corners of the box are similar sprockets on chain wheels 6 over which run endless chains 7, one on each narrow side of the box or frame, two complete loops being used.

Across the chains and secured to them, are two slats 8, one across each viewing panel so that as the endless chains are moved one slat will pass upward over one panel and the other downward over the other panel.

To make both chains move in unison it suffices to secure any two of the opposite sprocket wheels to the same one of shafts 9. The slats are provided with opposed hooks 8', which, when the slats are moved from end to end of the opposite panels, alternately hook and release the successive curtains from the reels by engaging grooves 19', which are formed in a curtain rod 19 secured to the end of the curtain and having shoulders 19' disposed so as to bear on the opposed faces of the heads to prevent

longitudinal movement or skewing of the rods and thereby preserve their alignment.

In Figures 2, 7, 8 and 16 are shown pivoted pawls 10, which are adapted to strike pins 11 on the reel in order to accomplish the alternate hooking of the respective hooks 8' into the grooves 19² and their release therefrom. Pivoted hooks 12 also engage the pins of the reels to prevent backward movement of the reels.

A friction brake 13 on any corner sprocket stabilizes the traveling slats to compensate for unbalanced curtains, etc. The curtain rolls are similar to the standard spring 15 shade rollers but preferably of metal tubing, and are inserted in the reels with their pivots projecting into the heads of same. Figure 4 shows the usual flattened pivots 14 which maintain the springs of the rollers 20 tensioned. These pivots are disposed in notches on the inner side of the annular portions 5 of the reel heads, and are locked against displacement by disks 5'. One of these disks is shown in Figure 4 as being 25 disposed within the annular part 5 with its periphery bearing on the pivots 14, the notch 15 being provided in the disk so that when the disk is turned to allow the notch to release any pivot, one end of the roll may 30 be disengaged from the reel. The reel has a central shaft 16 having bearings in both sides of the frame, and around one end of the shaft is a groove 17 into which a keeper 18, pivotally secured to the frame 35 adjacent the bearing, is adapted to engage to maintain the reel in place, or permit its bodily removal from its bearings by longitudinal shifting and tipping of the reel. A spring cam 16' is removably secured to the shaft 16 and operates to prevent lateral movement of the keeper 18 and lateral displacement of the disk 5'.

To actuate the endless slat carrying chains we employ a third endless driving chain 40 20. This drive chain 20 passes over small sprocket wheels similar to those for the other chains, two of them idling on the upper and lower shafts 9 shown on the left of Figure 2, and the others being variously positioned as indicated at 21. The endless drive chain is driven from one of the small 45 sprocket wheels 21² secured to a short shaft 22' which is journaled in a frame 23'. A pulley 27 is secured to the shaft 22', and a belt 27' connects the pulley with a motor 26.

The drive chain follows the direction of the arrows and will be observed to have two strands A and B, which parallel one of the traveler chains, and it is manifest therefrom that any finger or lug projecting from a link of the drive chain will pass along the traveler chain first in one direction and then in the opposite direction, with an interval of time between reversals depending 50 on the remaining length of loop through

which the finger must travel before returning. Such a finger is indicated on the drive chain at 22 and it is arranged to strike a device 23 on one of the traveling slats in both directions of travel to carry the slat 70 (and thereby both traveler chains and the other slat) first one way, then the other way the length of the viewing panel.

On the downward travel the finger leaves the device in rounding the sprocket 21' but 75 on the upper stroke, the sprocket being beyond the desired travel, the device trips off the pin or finger at the desired point.

No great importance attaches to the exact construction of this trip as many can be 80 suggested, but Figure 8 indicates the arrangement in relation to the chain strands. In Figure 8, when the finger is on the upward moving strand A it engages under a pawl 24 on the device 23 which rides along 85 a vertical track 25 and when at the highest point desired the pawl trips through an opening 25' in the track to pass the fingers. Figures 11 and 12 indicate the operation described without undue elaboration. 90

Besides carrying the curtain slats back and forth to unroll the successive displays, et cetera, the actuating finger 22 has another function, that of tripping the electric light switches to light up intermittently in any 95 prearranged manner, inside or outside lamps, singly or in any desired groupings.

The inner and outer lamps are indicated in the drawings at 28 and are connected through any desired circuits (not shown) 100 with certain or groups of tripping switches 29. These switches are all operated from within the apparatus by the finger 22 in passing along its journey in the manner indicated in Figure 3, in which 30 is a vertical rock shaft which has adjustable arms 31 for tripping all or groups of switches. The shaft is rocked by the chain finger in passing by striking other arms 32, and the switches are also variously thrown in or 110 out by the finger in passing along by striking the switch arms 33. The shaft may be divided in the center, as shown in Figure 3, in order to further split the circuits, according to the arrangement of the arms 31 115 for tripping the switches. 115

Figures 13 and 14 show in detail certain parts of the switches and trips. The arrangements shown in Figures 3, 13 and 14, 120 may be employed for illuminating the glass panels 3 and directing light into the area between the observer and the panels, so that the latter may function as mirrors, which will be had when the exteriorly disposed reflectors 28 supported upon the top of the cabinet in Figure 2, are lighted. A subsequent and different effect may be had when the reflectors are extinguished and when the lamps 28 at the upper and lower corners 125 of the cabinet, or when the groups of lamps 130

at the central portion of the cabinet, as shown in Figure 2, are lighted. Lamps of different colored glass may be employed for the said corner and groups sets, and these 5 may be successively lighted or one or more may be lighted at a time, whereupon the usual effects from illuminating the curtains by directing light first upon their outer faces and then upon their inner faces will 10 be had.

In Figure 3 the rock shaft sections 30—30 are arranged one above the other and each is provided with a plurality of arms 31 arranged in spaced relation. These arms are 15 shown in detail in Figures 13, 14 and 15. The arm 32 at the upper end portion of the upper shaft 30 and the arm 32 at the lower end portion of the lower shaft section 30 are disposed parallel. The upper 20 arm 35 is disposed so as to extend in a direction opposite to the arms 31 which are located on the shaft section 30. The arms 32 extend into the path of movement of the pin 22 on chain 20 and each of the arms 35 25 abuts one end of a slide bar 36 arranged in bearings 37. 38—38 are a pair of overbalanced angular-shaped levers respectively disposed adjacent to the end portions of the casing 1. The weighted side portions 30 of these levers are maintained in the vertical by stops 39, and the opposite side portions project into the path of movement of the pin 22 of the chain 20.

In Figure 3 it is to be noted that the 35 slide bars 36 are spaced at one end from the weighted side portions of levers 38. With this construction it is to be noted that when pin 22 abuts, for instance, the upper arm 32, the upper shaft section 30 will turn until 40 the pin 22 moves beyond the arm 32 and at the same time arm 35 operates slide bar 36 to move into contact with the weighted side portion of the upper lever 38. When pin 22 moves into contact with lever 38, the latter 45 operates slide bar 36 and upper shaft section 30 to move to the positions shown in Figure 3. The purpose of this construction is to effect the opening of the tripping switches 29. It is to be noted that each of 50 these switches consists of a slide bar 40 disposed in bearings 41 and arranged with its ends in alignment with one of the arms 31 and the weighted side portion of an overbalanced angular shaped lever 42, a stop 43 being provided for holding the weighted side of the lever in the vertical and the opposite side in the path of movement of the pin 22. As will be noted, each lever is connected to 55 a plate 44 disposed so as to move into and out of contact with a terminal 45 in each reciprocation of the slide bar 40, the slide bar being of metal and forming part of the circuit control of the switch. The arms 31 and levers 42, however, are of non-electrical 60 conducting material.

In Figure 3, pin 22 is shown as moving into contact with one of the levers 43. When pin 22 moves beyond the said lever, the latter will have moved the remote end of slide bar 40 into contact with the adjacent arm 31 and 50 in the movement of the said bar, contact plate 44 is rocked on its pivot 46 so that its free end is turned into contact with terminal 45. One of the electric circuits is then closed and the lamp or lamps thereof illuminated. 75

As the pin 22 continues its movement, the successively disposed switches 29 in connection with the upper rock shaft 30 are operated in the manner just described. The switches 29 in connection with the lower rock 80 shaft 30 are successively operated by the finger 22 as will be noted from the direction of movement indicated by the arrows for the chain 20. It is to be noted that pin 22 when moving into engagement with a lever 35 90 47 in the lower end portion of the casing moves the said arm out of the position shown whereupon lower slide bar 36 which is connected to lever 47 and also bearing upon arm 35 operates the latter to turn shaft section 95 30 so that when the pin 22 moves to the left and beyond lever 47, lower arm 32 is then in the path of pin 22 and operated thereby to turn the lower shaft section 30 which when turned by the arm 32 operates to restore 100 slide bar 36 and lever 47 to their original positions. When pin 22 operates the slide bars 40 to move into contact with the arms 31 of the upper shaft section 30 and finally moves into contact with the upper arm 32, the said arm 32 then operates to turn upper shaft section 30 which by turning actuates arms 31 to restore slide 105 bars 40 to the positions shown in the upper portion of Figure 3 and, at the same time to open the circuits to the lamps by actuating plates 44 to move to the positions shown. When pin 22 moves into contact with depending lever 47, the lower section of rock 110 shaft 30 operates the lower series of slide bars to open the electrical circuits to the lamps and when the pin 22 moves into contact with the lower arm 32, the rock shaft 30 is returned to its initial position and with it the lever 42. In like manner, the actuation of the upper slide bar 36 on the part of lever 38 operates to restore the upper rock shaft section to its original position after the same has been actuated to turn by the pin 22. 115

While the apparatus shown discloses opposite viewing panels, one panel only may be used, or the curtain hooks may be temporarily removed from the rear panel traveling slat to render that panel inoperative when so desired. 120

The operation of the device is as follows:

When the parts positioned as shown in Figure 2 and the chains 7 and 20 move in the direction of the arrows, the hooks 8' on the slat at the upper right corner portion 125 130

of the cabinet engage the opposite end portions of the rod 19 after the beginning of downward movement of the slat 8. This has the effect of unwinding the curtain to 5 which the rod 19 is connected. The slat 8 continues its downward movement until the curtain extends completely over the area directly behind plate 3 at which time pawl 10 on the lower side of slat 8 adjusts the 10 lower right reel by striking one of the pins 11 thereof. This adjustment of the reel takes place after the lower hook, as shown in Figure 8, passes below the rod next to be engaged. Now when slat 8 moves upwardly, 15 lower hooks 8' of Figure 8 will engage the adjacent rod and thereby unwind a curtain from the lower reel until the said curtain is extended across the opening of the frame and the parts returned to the position shown 20 in Figure 2. During the upward movement of slat 8, the spring of the curtain engaged by the upper hooks 8' operates to wind the curtain as the same is fed by the upward movement of the slat, and the pawl 12 on 25 the right of Figure 2 prevents backward movement of the reel. When the upper curtain is completely wound, the upper hooks will have moved upwardly and beyond the curtain rod and the upper pawl 10 in Figure 8 will then have engaged one of the pins 30 11 and thereby turned the upper reel so that in the downward movement of the slat 8 the upper hooks will engage the curtain next to that first engaged. The operation of the 35 parts on the left of Figure 2 being identical with those on the right, no further description of the parts on the left is necessary. In that the slats 8 and the chains connected thereto are operated by the finger 22 of 40 chain 20 engaging the pawl 24 shown in Figure 8 and located on the slat on the left of Figure 2, it is obvious that when the said finger moves out of engagement with the pawl as it does when the chain rounds the 45 wheels 21, 21', the slats will remain stationary for a definite length of time determined by the distance through which the finger moves around the several wheels before re-engaging the slat 8 on the left of Figure 1. 50 Having thus described our invention and indicated its improvement over the former apparatus of similar character, we claim:

1. In a curtain sign exhibitor, a rectangular frame having two spaced viewing panels; 55 chain wheels at the ends of the frame; two endless chains passing over the wheels, one at each side of the frame and extending along the sides of the viewing panels; a plurality of rolled display curtains supported 60 within the frame; two traveling slats, extending, respectively across each viewing panel with the ends secured to the chains and adapted to travel the length of the panels therewith; and means for simultaneously 65 actuating the chains intermittently in re-

verse directions, the slats being adapted to engage the free ends of the curtains and arranged on the chains so that one will travel in one direction across its panel while the other slat travels in the opposite direction 70 across its respective panel, and thereby the curtains are unrolled simultaneously.

2. In a curtain sign exhibitor, a rectangular frame; chain wheels at the ends thereof; endless chains passing therearound and extending along the sides of the frame; a rolled curtain supported in the frame; a traveling slat for unrolling the curtain, the slat being secured to the chains; means for simultaneously actuating the chains, said 75 means embracing a shaft; two oppositely disposed wheels secured on the shaft; an endless chain trained around each wheel; a third endless chain having a strand adjacent to one of the two chains; means for 80 actuating the third chain; and means for imparting motion from the third chain to an adjacent chain.

3. In a curtain sign exhibitor, a rectangular frame; chain wheels at the ends thereof; 90 endless chains passing therearound and extending along the sides of the frame; a rolled curtain supported in the frame; a traveling slat for unrolling the curtain, the slat being secured to the chains; means for simultaneously actuating the chains, said means embracing a shaft; two oppositely disposed wheels secured on the shaft; an endless chain trained around each wheel; a third endless chain having reverse running 95 strands adjacent to one of the two chains; means for actuating the third chain; and means on the third chain for imparting movement in opposite directions to an adjacent chain.

4. In a curtain sign exhibitor, a rectangular frame; chain wheels at the ends thereof; endless chains passing therearound and extending along the sides of the frame; a rolled curtain supported in the frame; a 100 traveling slat for unrolling the curtain, the slat being secured to the chains; means for simultaneously actuating the chains, said means embracing a shaft; two oppositely disposed wheels secured on the shaft; an endless chain trained around each wheel; a third endless chain having a strand running 105 adjacent to one of the two chains; means for actuating the third chain; and a finger on the third chain, said finger being adapted to engage the slat and to move the same together with the chains in either of two directions.

5. In a curtain sign exhibitor, a rectangular frame; chain wheels at the ends thereof; 110 endless chains passing therearound and extending along the sides of the frame; a rolled curtain supported in the frame; a traveling slat for unrolling the curtain, the slat being secured to the chains; means for 115

simultaneously actuating the chains intermittently in reverse directions, said means embracing a shaft; two oppositely disposed wheels secured on the shaft; an endless chain trained around each wheel; a third endless chain having reverse traveling strands adjacent to one of the two chains; means for imparting a continuous motion to the third chain; and a finger on the third chain, said finger being adapted to engage the means on the slat in both directions of the third chain's travel.

6. In a curtain sign exhibitor, a frame, a reel of curtain rolls at each end thereof, a pair of traveling chains at the sides of the frame, a slat across the frame secured to the chains, means for actuating the chains

with an intermittent reversing motion to move the slat back and forth across the frame, means on the slat for engaging and disengaging the curtains from both reels for displaying them across the frame, and means on the slat for engaging and turning the reels at the ends of the travel of the slat to bring a fresh curtain into relation with the engaging means.

7. In a structure as recited in claim 6, means for preventing a reverse motion of said reels.

8. In a structure as recited in claim 6, means for braking the slat-carrying elements.
